of which apparatus is provided with a resilient base 16 which rests on the floor. A front end wall 2, a rear end wall 3, front and rear side walls 4, 5, respectively, and a bottom wall 6. A closure plate 7 is detachably secured on top of the tank 1 by suitable latches 8.

UNITED STATES PATENT OFFICE

DISHWASHING APPARATUS OF THE GEAR-DRIVEN ROTARY BRUSH TYPE

David O. Semel, Los Angeles, Calif.

Original application March 8, 1944, Serial No. 525,558. Divided and this application December 3, 1947, Serial No. 789,395

1 Claim. (Cl. 15—74)

My invention relates to improvements in dishwashing apparatus of the type forming the subject matter of my co-pending application, Ser. No. 525,558, filed March 8, 1944, and of which the instant application is a division and now Patent 2,435,240 dated February 3, 1948.

The primary object of the instant invention is to provide inexpensive, light-weight, portable apparatus for pressure spraying dishes, pots, pans, and the like cleanly and quickly without breaking china and similar material and which is equipped with especially effective and convenient means for brush-cleaning glassware, cups and bowls.

Other and subordinate objects, within the purview of my invention, together with the precise nature of my improvements, will be readily understood when the succeeding description and claim are read with reference to the drawings accompanying and forming part of this specification.

In said drawings:

Figure 1 is a view in plan of my improved apparatus in a preferred embodiment thereof with the closure plate removed; and

Figure 2 is a view in longitudinal section taken on the line 2—2 of Figure 1 with the closure plate in place.

Referring to the drawings by numerals, my improved dishwashing apparatus, as illustrated, comprises an elongated, rectangular tank 1 which includes a front end wall 2, a rear end wall 3, front and rear side walls 4, 5, respectively, and a bottom wall 6. A closure plate 7 is detachably secured on top of the tank 1 by suitable latches 8.

The tank 1 is designed to be used on a sink installation, not shown. For supporting the tank and levelling the same on such an installation, rod-like corner legs 11 are provided thereon which are vertically adjustable in guide sleeves 12 with wing nuts 13 therein for holding said legs in adjusted position.

A water feed pipe 14 extends along the bottom wall 6 within the tank 1 in the longitudinal center of said tank with its front end extending out of the front end wall 2 and threaded, as at 15, for coupling a hose line, not shown, thereto, said pipe having an upstanding, enlarged rear end section 16 adjacent the rear end wall 3, a circumferential collar 17 at the base of the enlarged section 16, and sealing collars 18 on its front end portion upon opposite sides of the front end wall 2. Suitable clips 19 secure the water feed pipe 14 to the bottom wall 6.

A cylindrical gear-driven brush unit has a base 20, a weight 21 and a stand 22 to which stand 21 a piston 23 is fitted to move up and down in the base 20. A brush 24 is mounted on the piston 23. A spray head 25 is mounted on the stand 21.

A funnel-like sprayer is provided at the top of the enlarged section 16 comprising a perforated body 20 and a tubular stem 21 extending part way up into the body 20 and downwardly into

said section 16 in which said stem is telescopically fitted for removal out of the section 16. A pin 22 in the section 16 and a bayonet slot 23 in the lower end of the stem 21 provide for detachably securing said sprayer to said section 16.

A transverse, foraminous partition 24 is provided in the body 20 of said sprayer just below the upper end of the stem 21. A suitable closure cap 25 is threaded onto the upper end of the body 20 of said sprayer for closing said top. The closure cap 25 is suitably spaced from the closure plate 1.

A cylindrical basket 26 of wide mesh wire material surrounds the section 16 and the body 20 of said sprayer concentrically thereof, the bottom of said basket 26 being provided with an axial, annular washer 27 rotatable about the section 16 just above the collar 17 and designed to engage said collar if the bottom of the basket 26 sags under weight thereon.

A ring gear 29 surrounds the upper edge of the basket 26 and to which said edge is suitably attached. The ring gear 29 is supported by four gear pinions with which said gear 29 meshes and thereby suspends the basket 26 for rotation

about the axis of the section 16 and said sprayer, there being three gear pinions 29, 30, 31 of like size suitably mounted for rotation about horizontal axes on the front and rear side walls 4, 5 and on the rear wall 3 to support said gear pinion 29 at the sides and rear of the basket 26.

The fourth gear pinion 32 is larger than the others and supports the ring gear 29 at the front side of the basket 26, said pinion 32 being fixed in any suitable manner on the rear

end of a short horizontal shaft 33 journaled in transverse bars 34 in said tank 1 to extend horizontally in the longitudinal center of said tank. The shaft 33 forms part of a brush unit including a disk-like head 35 having an axial sleeve

36 detachably secured on the front end of the shaft 33 by a pin and bayonet slot connection 37, 38. A pair of diametrically opposite arms 39 extend forwardly from the head 35 with rear ends pivoted, as at 40, to said head, and suitable

bristle brushes 41 fixed on their front ends. A coil spring 42 suitably attached to said arms 39 tends to separate said arms and brushes 41.

In one front corner of the tank 1 is an upstanding drain pipe 42 having its lower end ex-

tending out of the bottom wall 6 of said tank, as

at 43, and its upper end terminating slightly below the upper edge of the basket 26. Longitudinal slots 44 in the lower end of said drain pipe 42' provide for draining the tank out of the lower end 43 of said pipe. A combined overflow and drain closing pipe section 44' is vertically slidable in the drain pipe 42'. A bayonet slot 45 in the drain pipe 42' and a pin 46 on the pipe section 44' working in said slot provide for adjusting the pipe section 44' into a set, raised position in which its lower end clears the slot 45 and thereby opens the drain pipe 42'. The slot 45 is so arranged that a pipe section 44' may be lowered in the drain pipe 42' to close the slot 46 and thereby close said drain pipe, and said pipe section is so constructed that when it is thus lowered, its upper end is at the same level as the top edge of the basket 26. Thus, it will be seen that the pipe section 44', when lowered, functions as an overflow pipe to maintain water introduced into the tank 1 at the level of the top edge of the basket 26.

A suitably arranged crank 51 is provided for operating the gear pinion 29 journaled on the front side wall 4.

Referring now to the use and operation of the described invention, the body 20 of the described sprayer is designed to be filled with soap flakes above the partition 24 and the basket 26 to be filled with dishes or the like, not shown. In filling the basket 26, the sprayer may be removed in the manner already described and then replaced. Water introduced into the pipe 14, under pressure, and through the medium of a suitable hose connection, issues from the body 20 of the sprayer in spray form and the soap flakes in the body 20 render the sprayed water soapy. The dishes are thus sprayed with soapy water until the level of the water in the tank 1 rises to the overflow limit, at which point the spray 40 acts to agitate the water and thereby facilitate the cleaning of the dishes. By means of the crank 51, the basket 26 may be revolved to further facilitate the washing operation. Glasses and the like may be cleaned by means of the 45 brushes 41 which, as will be understood, are revolved by the gear 32. The arms 39 of the brush unit may be pressed together manually to facilitate entering the brushes 41 in a glass, cup,

bowl, or pitcher. The described sprayer may be readily removed from the section 16 for cleaning, likewise the basket 26, by merely lifting the ring gear 29' off of the described gear pinions. The manner in which the tank 1 may be drained has already been described.

The foregoing will, it is believed, suffice to impart a clear understanding of my invention without further explanation.

Manifestly, the invention, as described, is susceptible of modification without departing from the inventive concept, and right is herein reserved to such modifications as fall within the scope of the appended claim.

Having described the invention, what is claimed as new is:

In a dishwashing apparatus, a tank, a rotatably mounted brush unit in said tank including a horizontal journaled shaft, a crank on one side of the tank rotatable about a horizontal axis, and means operative by said crank to rotate said shaft at a relatively different speed comprising a circularly arranged series of gears in said tank rotatable about horizontal axes, a ring gear surmounting and meshing with the series of gears and supported solely thereby, one gear of the series being fast on said crank, and another gear of the series being fast on said shaft and of different diameter than the other gears of the series.

DAVID O. SEMEL.
